UNITED STATES PATENT OFFICE.

THOMAS GIBSON, GEORGE ALFRED FARMER, AND EDWARD READ, OF BURTON-UPON-TRENT, ENGLAND.

SIGNAL-OPERATING MECHANISM.

1,129,479.

Specification of Letters Patent. Patented Feb. 23, 1915.

Application filed May 29, 1913. Serial No. 770,724.

To all whom it may concern:

Be it known that we, THOMAS GIBSON, GEORGE ALFRED FARMER, and EDWARD READ, subjects of the King of England, residing at Burton-upon-Trent, in Staffordshire, England, have invented certain new and useful Improvements in Signal-Operating Mechanism; and we do declare the following to be a full, clear, and exact description of the invention, such as will enable others skilled in the art to which it appertains to make and use the same.

This invention relates to railway signaling, and more especially to track instruments for actuating electric signals; and the object of the same is to produce a device of this character and employ a system whereby on the approach of a train toward a point of danger or a signal tower the engineer is notified whether there is danger ahead or not. For instance, in the system illustrated herewith he is notified as he passes a block signal post (whose signal he may not be able to see on account of fog) what the exact setting of that signal is at that moment.

A detail also useful in the system employed for carrying out our invention is a checking signal by which the operator in 30 the nearest tower is automatically notified when the engine or train passes any and every given point, such as the posts along the block signal system.

Still another object of the invention resides in providing a movable track instrument with improved pockets or the like for the reception of portions thereof in certain positions of said instrument.

Other details will appear in the following 40 specification and claims, and the entire device is shown in the accompanying drawings wherein—

Figure 1 is a plan view of the signal operating mechanism; Fig. 2 is a side elevation thereof; and Fig. 3 is a longitudinal section therethrough as seen on the line 3—3 of Fig. 1.

In describing the invention, we wish to refer to the drawing in which similar reference numerals designate corresponding parts throughout the several views and in which—

P designates a post of a block signal disposed immediately adjacent a trackway, the signal proper (not shown in the drawing)

being connected by a rod R with a weighted lever constituting its actuating mechanism M. The weight of this lever is overcome by a pull on a chain or wire W which disposes the signal to its various positions. Any suitable type of actuating mechanism 60 may be employed but the chain or wire W will lead to a remote point which in the present instance we may assume to be a tower wherein is located an operator who controls the setting of the signal on the post. 65

Coming now more particularly to the details of the present invention, the numeral 1 designates what might be called a shoe which by preference consists of a piece of T-iron having downturned ends 2 as shown, 70 and in length it is sufficient to extend over from six to twenty ties—those at the extremities of the group spanned by it carrying metal pockets 3 into which the ends 2 of the shoes will drop so that no one can catch 75 his foot beneath them. These members which are termed pockets consist of strips or plates on which are formed or otherwise secured, casings or housings which open upwardly and increase in depth toward one end thereof to form recesses or cavities. These cavities or recesses, as stated above, receive the downturned ends of the shoes therein when said shoes are in their lowermost positions with respect to the rail sections and in 85 this sense, these devices may be said to be pockets. There are two such shoes, but as they are duplicates we are describing but one. They are by preference located inside the rails and slightly spaced from them as 90 seen in Fig. 1, and they stand about opposite each other and about opposite to the pole P in the present illustration. Plates 5 secured beneath the extremities of certain ties carry bearings 6 in which are mounted rock shafts 95 7 extending across the track beneath its rails, and projecting rigidly from each shaft is an arm or a pair of arms 8 pivoted at 9 to one shoe, and another arm or pair of arms 10 standing at an angle to the first arm or pair 100 of arms and pivoted at 11 to the other shoe. Three of said shafts are shown in the device illustrated in Fig. 1, and as shown in Fig. 2 the upstanding arms 10 support the shoe 1 in raised position while the other arms 8 105 support the opposite shoe 1' in lowered position. From this description of the parts of the device, it will be understood that one

of said shoes, in the position last mentioned, is adapted to be engaged by a circuit closer on a moving object on the trackway, while the other shoe is in its ineffective position 5 and out of possible engagement with a circuit closer on the moving object.

It is a well known fact that persons at 10 times walk along and across the railroad tracks and this is particularly true of animals and in view of the particular devices herein shown for the purpose of completing the circuit, it is deemed necessary to provide some means to prevent any possibility of the feet of persons or the hoofs of animals from 15 being engaged therewith. We, therefore, provide, as stated previously, the pockets 3 for the reception of the downturned ends of the shoes when the latter are in their lowermost positions. When so disposed and received 20 in the pockets as mentioned, it will be appreciated that persons' and animals' lives will not be endangered by any possibility of engagement with the ends of these shoes.

The actuating devices for the mechanism 25 thus far described may be any which will successfully perform the office, and as typical of one arrangement which will operate successfully in conjunction with the block signal, we will describe that shown in the 30 drawings.

One of the rock shafts 7 is projected at 35 one extremity as at 7', and attached rigidly thereto is an arm 15 carrying at its outer end a weight 16—the disposition of this arm and the size of this weight being such that it will normally hold the parts in the 40 position shown in Fig. 2.

The setting or actuating device for the signal operating mechanism thus far described 45 may be moved by hand to reverse the position of parts, by merely lifting the weighted arm 15; but in the illustration we have shown one means for connecting said setting devices with the signal operating devices heretofore described by the use of reference letters. That is to say, an upstanding arm 17 is rigidly mounted on the projecting end 7' of the shaft referred to, and this is connected by a wire 18 with the block- 50 signal wire W as seen in Figs. 1 and 2. When the signal operator in his tower draws on the wire W to set the signal on the post P at danger, draft on the wire W is imparted through the wire 18 to the upstanding 55 arm 17 with the result that the shaft 7' is rocked in its bearings and the weighted arm 15 is raised, so that the other shoe is elevated and the one now shown as raised is depressed. On the contrary, when the block 60 signal is set at safety, the parts will be restored to their normal position, the shoes will be reversed, the corresponding circuit closer on the moving object will be struck by the raised shoe, and a "clear" signal will 65 be given to the engineer. In any event, how-

ever, it is our purpose to give some kind of a signal to the engineer when he is passing a danger point such as a block signal.

In connection with the above-described signal operating mechanism, and the actuating devices therefor, we make use of a checking signal whereby the operator within the signal box may be notified when a locomotive or train passes the post P. As herein shown this comprises a rather long 70 and flat bar 20 disposed just inside one of the track rails where the flanges of the wheels will strike and depress it, said bar being supported at one end as at 21, free at its other end, and guided vertically in its 75 movements by an upright flange 22 forming part of a water-tight box 23 mounted on and carried by the sleepers at about the mid-length of said bar; and depending from the latter through the top of this box is a terminal (not shown). Disposed within the 80 box are spring terminals for coöperation with the aforesaid terminal so as to complete a circuit between them. These last 85 named terminals are respectively connected 90 with wires 27 which are insulated from each other and mounted within a small tube or pipe 28 that leads alongside the track to the signal tower. Herein is adapted to be located a signal of any desired character. The 95 length of the bar is such that at least two of the trucks of the ordinary train or car must be constantly over it, and therefore when a train passes this device it closes a circuit 100 through the signal in the tower and informs the operator stationed there that the locomotive has passed the post P, so that he checks up its position and is then at liberty to 105 change the signal at this point to indicate a clear block at one point and an occupied block at another point. In the act of changing 110 this signal, he alters the position of the shoes 1 and 1' by the means above described. This detail constitutes part of the block signaling mechanism, and we have shown and described it briefly in order that the complete system which includes our improved signal operating mechanism may be understood.

What is claimed as new is:

1. In a signal operating mechanism, the combination with a plurality of rail ties and a pair of track rails mounted thereon; of shoes of elongated design operatively mounted on said ties immediately adjacent the 115 rails, said shoes having downturned ends, means for raising and lowering said shoes to dispose the same to their operative and inoperative positions respectively, and plates secured to the upper faces of the end pairs of ties spanned by said shoes, said plates being provided with recesses increasing in depth toward one end thereof to form pockets for the reception of the downturned ends of the shoes when the latter are dis-

posed to their lowermost positions and portions of said pockets abutting the side faces of certain of said pairs of ties.

2. In a signal operating mechanism, the combination with a plurality of rail ties and a pair of track rails mounted thereon; of shoes of elongated design, operatively mounted on said ties adjacent the rails, said shoes having downturned ends, means for 10 raising and lowering said shoes to dispose the same to their operative and inoperative positions, respectively, plates secured to the upper faces of the end pairs of ties spanned by said shoes, and pockets formed integral 15 with said plates to project therebelow and increasing in depth toward one end thereof

for the reception therein of the downturned end of the shoes, the increasing of said pockets in depth at one end thereof providing shoulders for abutment against the inner side faces of the outer end ties to which said plates are secured. 20

In testimony whereof we have hereunto set our hands in presence of two subscribing witnesses.

THOMAS GIBSON.

GEORGE ALFRED FARMER.
